UNITED STATES PATENT OFFICE.

CHARLES E. HOPPES, OF SPRINGFIELD, OHIO, ASSIGNOR TO THE EVERWEAR MANUFACTURING COMPANY, OF SPRINGFIELD, OHIO, A CORPORATION OF OHIO.

PLAYGROUND APPARATUS.

Application filed April 16, 1923. Serial No. 632,237.

To all whom it may concern:

Be it known that I, CHARLES E. HOPPES, a citizen of the United States, residing at Springfield, in the county of Clark and State of Ohio, have invented certain new and useful Improvements in Playground Apparatus, of which the following is a specification.

My invention relates to improvements in playground apparatus, particularly to that kind of apparatus known as the ocean wave in which a revolving platform is hung from the upper end of a vertical standard in such a way that the platform as it revolves may have a pivoted swinging sidewise motion.

The object of my invention is to provide a rotatable bumper and antifriction device for the platform located at the lower end of the standard for the purpose of eliminating wear between the platform and standard, and also to reduce friction between the platform and standard to allow for a more free rotation of the platform.

Referring to the drawings:

Fig. 1 is a view of an apparatus embodying the improvements.

Fig. 2 is a vertical section of the upper portion of the support standard and the platform support.

Fig. 3 is a sectional view of the lower portion of the standard and the bumper.

Fig. 4 is a side elevation of a portion of the platform support.

Referring to the drawings, 1 represents a series of platform members preferably constructed of wood and arranged in circular fashion with adjacent ends connected together by metallic plates 2. An inner ring 3 is also preferably provided which is rigidly connected to the respective platform members by the arms 4. A central standard 5, preferably of tubular form, has its lower end embedded in cement 6 so as to maintain the standard rigidly in a vertical position. Inserted in the upper end of the standard is the reduced wing-shaped neck 6 of a semi-cylindrical head 7, upon which rests the semi-cylindrical portion of a cap 8. The cap 8 has a plurality of pairs of ears 9 and between each pair of ears is rigidly clamped the upper end of a metallic rod or strip 10, the lower end of which is pivotally connected to one of the metallic plates 2. The cap 8 is preferably provided with an oil cup 11, and an orifice 12 for lubricating purposes.

Rotatably mounted upon the lower end of the standard 5 between collars 13 and 14 is a disk or wheel 15 preferably of wood. Each one of the collars is secured to the standard by a wedge 16 and bolt 17, the collar being provided with an offset portion having a pocket 18 to receive the wedge.

In operation, the ring 3, as the platform swings from side to side during its revolving motion, comes in contact with the rotatable bumper and antifriction device to eliminate friction between the ring and the standard, thus preventing wear on the standard to an extent which would endanger its supporting capacity, and also acts to cushion the platform and reduce friction to allow for the free rotation thereof.

The rotatable bumper also prevents the swing from swaying back and forth, as the tendency in practice is for the inside ring 3 to remain in contact with the bumper at all times when in use, because the bumper rotates and therefore does not have a tendency to cause the swing to rebound as would be the case with the ring contacting the post.

Having thus described my invention, I claim:

1. In an apparatus of the character described, a vertical supporting standard, a platform revolvably hung from the upper end of said standard in a manner to permit sidewise swinging movement of said platform, and a bumper rotatably mounted on said standard with which said platform contacts in its sidewise movements, for the purpose specified.

2. In an apparatus of the character described, a vertically-arranged standard, a platform revolvably hung from the upper end of said standard in a manner to permit sidewise swinging movement of said platform, a pair of collars clamped to said standard near the lower end thereof, and a disk rotatably mounted on said standard between said collars in the path of said platform as it swings sideways.

3. In an apparatus of the character described, a vertical standard, a platform revolvably hung from the upper end of said standard in a manner to permit sidewise swinging movement of said platform, said platform having an inner ring, and a rotatable bumper mounted on said standard in the path of said ring as the platform swings sidewise.

4. In an apparatus of the character described, a vertical supporting standard, a rotatable support at the upper end of said standard, a series of downwardly projecting rods hinged to said support, a circular platform connected to the lower ends of said rods, an inner ring connected with said plat-

form in spaced relation with said standard, and a rotatable buffer supported by said standard in the path of said ring.

In testimony whereof, I have hereunto set my hand this 9th day of March, 1923.

CHARLES E. HOPPES.
